UNITED STATES PATENT OFFICE.

ROSE A. WETZEL, OF BUCKHANNON, WEST VIRGINIA.

JAR-HOLDER.

1,060,048.

Specification of Letters Patent.

Patented Apr. 29, 1913.

Application filed August 24, 1912. Serial No. 716,940.

To all whom it may concern:

Be it known that I, ROSE A. WETZEL, a citizen of the United States, residing at Buckhannon, in the county of Upshur and State of West Virginia, have invented a new and useful Jar-Holder; and I do hereby declare the following to be a full, clear, and exact description of the invention, such as will enable others skilled in the art to 10 which it appertains to make and use the same.

This invention relates to a new and useful jar holder adapted for holding preserving jars and the like while being filled and 15 sealed.

As one of the objects of the invention, it is the aim, to provide a holder comprising upper and lower annular members, one to surround the upper portion of the jar, while 20 the other receives the base of the jar, and which are connected and braced by the vertical stays as shown, which terminate in angular members or hooks, which not only engage under a shoulder at the top of the 25 jar, but are also adapted to hook over the edge of a vessel, to steady the jar and the holder while the jar is being filled, as shown in Figure 1.

The invention comprises further features 30 and combinations of parts, as hereinafter set forth, shown in the drawings and claimed.

In the drawings:—Fig. 1 is a view in perspective of a preserving jar, showing the 35 same supported by the improved holder, Fig. 2 is a detail view of the holder detached from the jar, and illustrating a member, device or ladle for packing the preserves or fruit in the jar. Fig. 3 is a view showing a 40 slightly modified form of holder. Fig. 4 is a sectional view on line 4—4 of Fig. 2.

Referring more particularly to the drawings 1 designates a preserving or fruit jar of the usual construction having a shoulder 45 at its upper portion, which is denoted by the numeral 2, while 3 designates the jar holder, which in Figs. 1 and 2 comprise the upper and lower members 4 and 5. These members 4 and 5 are annular in contour to 50 fit the jar, and are connected and braced by the vertical braces 6. These braces 6 in Figs. 1 and 3 terminate at their upper ends in angular portions or hooks 7, which are designed to not only engage under the shoulder 2 of the jar for supporting the same, 55 but are adapted to engage a vessel 8, as

shown in Fig. 1, for steadyng the jar and the holder therefor while the jar is being filled. Also connecting the members 4 and 5 is a handle 9 and brace 10. The handle 9 is made integral with the annular member 4. In Figs. 1 and 2 the annular member 5 is bottomless, but is provided with an inwardly extending flange 11 upon which the jar seats, and an outwardly extending 60 flange 12 trough-shaped in cross section, designed for the purpose of receiving the overflow or spilt fruit or preserves. The lower annular member 5 is constructed of a single piece of metal, bent to form a vertical flange 12 intermediate the inwardly and outwardly extending flanges, against which intermediate flange the lower side portions of a jar engage. In Fig. 3, however, the annular member 5 is constructed with a counter-sunken bottom 13. The holder may be constructed of any suitable size, for instance, of a size to either fit a half-gallon jar, a quart jar or pint jar. However in manufacturing this holder to fit either a quart or 70 pint jar, the same should be provided with a counter-sunken bottom, as shown in Fig. 3. In Fig. 2 the angular members or hooks 7 are dispensed with, and in lieu thereof the braces 6 terminate in eyes 14, in which hooks 75 may be connected, for suspending the holder. The upper annular member is provided with an integral strap 15, forming a holder, for the spoon or ladle 16, which may be used for pressing the fruit or preserves 80 compactly in the jar. 85

In the drawings there are disclosed certain features, but in practical fields these features may necessitate alterations, to which the patentee is entitled, provided the alterations are comprehended within the scope of what is claimed. 95

From the foregoing it is to be observed there has been produced a simple and efficient holder for jars and the like, and one 100 which has been found particularly desirable and practical.

The invention having been set forth, what is claimed as a new and useful is:—

A jar holder comprising upper and lower 105 annular members adapted to receive a jar, vertical braces connecting and bracing the upper and lower annular members relative to one another, and terminating in members adapted to engage under a shoulder on the jar, the lower annular member having an inwardly extending flange against which 110

the jar seats, and constructed with an outwardly extending annular flange trough-shaped in cross section adapted to catch the overflow of the fruit or preserves, the lower 5 annular member being constructed of a single piece of metal and bent to form a vertical flange intermediate the inwardly and outwardly extending flanges, a handle forming an integral part of the upper annular 10 member, and provided with a brace connect-

ing the lower member, and a ladle holder forming an integral part of the upper annular member.

In testimony whereof I have signed my name to this specification in the presence of 15 two subscribing witnesses.

ROSE A. WETZEL.
